L. P. VALIQUET.

PHONOGRAPH,

APPLICATION FILED OCT. 9, 1916.

1,406,249

Patented Feb. 14, 1922.

*Inventor
Louis F. Valiquet
By J. O. Ridder
His Attorney*

UNITED STATES PATENT OFFICE.

LOUIS P. VALIQUET, OF ELYRIA, OHIO, ASSIGNOR TO THE GENERAL PHONOGRAPH MANUFACTURING COMPANY, OF ELYRIA, OHIO, A CORPORATION OF OHIO.

PHONOGRAPH.

1,406,249.

Specification of Letters Patent. Patented Feb. 14, 1922.

Application filed October 9, 1916. Serial No. 124,490.

To all whom it may concern:

Be it known that I, LOUIS P. VALIQUET, a citizen of the United States, residing at Elyria, in the county of Lorain and State of 5 Ohio, have invented certain new and useful Improvements in Phonographs; and I do hereby declare the following to be a full, clear, and exact description of the invention, such as will enable others skilled in the art 10 to which it appertains to make and use the same.

My invention relates to phonographs and more particularly to improvements in the sound conducting means or resonators employed in such instruments. One of the objects of my invention is to provide, in devices of the class which I have mentioned, improved connecting means, between various parts of the sound conducting means or resonator, for joining together these parts so as to make it impossible to accidentally separate them, but which at the same time enables one who seeks to part them to be so readily and conveniently, and to reassemble them as 25 readily and conveniently, thereby, among other things, greatly facilitating packing and shipping of the machines. I also provide means which can be cheaply and conveniently manufactured, and which insures no 30 defective parts in the particular elements of the machines involved.

In a great many of the phonographs now used, the sound tube is divided up into two portions, the main part or stationary part 35 being either a portion of the frame or rigidly attached to the frame in some manner, and a second part, frequently spoken of as the tone arm and herein referred to as the sound conveyor or tone arm, is connected to the main 40 portion or amplifier at one end and to the sound box at the other. The sound conveyor is made to swing across the face of the record and in many types of phonographs, up and down in a plane perpendicular to the record.

I am aware that bayonet joint slots and pins have been provided for connecting the tone arm to the stationary part of the amplifier, but so far as I am informed, it has always been found necessary to leave one 50 arm of the bayonet slot open at the end, so that the pin may be accidentally withdrawn and the sound tube disconnected from the machine. This is a very objectionable feature, especially in small machines, which are 55 operated frequently by children or other in-

experienced persons who are apt accidentally or intentionally to disconnect the tone arm with the delicate sound box from the machine and injure the delicate parts of the sound box, or dent or otherwise injure the tone arm.

By my invention I provide apparatus of the class described in which there is no rattle or loose play between the tone arm and the part of the machine to which it is connected. I achieve this last mentioned object without interfering with the freedom of movement of the tone arm in the manner and directions desired. In other words, the tone arm may be freely swung up and down 70 and in azimuth through the desired ranges to perform its functions, and there will be no rattle at the pivot during the movement of the arm when it is at rest or when the phonograph is in operation.

The objects of my invention which I have named and others will appear and the invention will be better understood, I believe, from a description of an embodiment of the invention.

Fig. 1 is a section through a portion of an embodiment of my invention.

Fig. 2 is a perspective view of the bushing shown at 5 in Fig. 1.

Fig. 3 is an enlarged view of the collar and 85 throat.

Fig. 4 is a detail.

Fig. 5 is a section through the line 4—4 of Fig. 1.

Referring now to the drawing and to the 90 embodiment of the invention shown therein, at 7 is shown the frame of a phonograph and at 8 a portion of the amplifier or resonator. At 9 is shown a sound conveyor or tone arm. The sound conveyor 9 and the 95 amplifier are connected together through means including a throat, here shown as a hollow bushing 5, which also constitutes a part of the sound conducting means. The other end of the sound tube 9, as is well 100 understood, carries the sound box 9₁, stylus support 9₂, and stylus 9₃. In the form shown, the top wall of the main portion of the amplifier 8 is formed by the frame top 11, which is provided with an opening 12. 105 The bushing 5 is provided with a flange 13 about its bottom, through which it is connected to the top of the frame by suitable means, such as screws applied at the openings 14. The bushing 5 is also provided 110

with a collar 13, which fits within the opening 12. Slots 15 are formed in the top of the bushing 5, preferably by cutting away the edge for a certain distance, as shown in 5 Figs. 2 and 3. These slots are best of substantially equal length and positioned diametrically opposite each other.

The inner end of the sound tube 9 in the embodiment shown is provided with a collar 16 from which pins 17 project. In the embodiment shown a straight rod 18 extends across the sound arm and through openings 19 therein, and projects at 17 from both sides of the collar 16. When the apparatus 15 is assembled, these pins are in the slot 15.

Means are provided for retaining the sound tube in position when assembled, here shown as a collar 20, which is connected to the top of the bushing 5 by some suitable 20 means, such as threads 21, here shown as formed on the interior of the collar 20 and other threads 22 on the exterior of the top of the bushing 5, the threads 21 and 22 being adapted to co-operate. The top of the 25 collar 20 is turned inwardly to form a flange 23, which fits close about the collar 16 and prevents, through the co-operation with the pin 17, the removal of the sound tube.

I prefer to cut a recess 25 on the interior 30 of the member 20 between the threads 21 and the collar 23, in which the ends of the pins 17 are housed.

The margins 15₁, 15₂ of the upper part of the neck 5 are left upon the edge of the 35 neck and serve to hold the collar 16 within the neck (as shown best in Figs. 1 and 5) and prevent rattling of the parts. The exterior wall of the collar 16 is curved and its maximum diameter should be substantially 40 the same as that of the bore of the neck 5 at its top. I prefer to curve the outside surface of the collar 16 so that it shall form a zone of a sphere whose diameter is that of the maximum diameter of the collar. With 45 this arrangement the tone arm may be raised and lowered and turned freely in the horizontal, through the desired ranges to perform its functions, and yet the joint will be so tight that there will be no play and 50 no rattle.

The apparatus shown in the drawing may be assembled as follows: The collar 20 is slipped over the sound box end of the sound tube before the sound box is placed thereon. 55 The sound tube is placed upon the bushing 5 with the pins 17 in the slots 15 and the collar 20 is screwed down upon the bushing 5, the threads 21 and 22 co-operating to fasten the parts together. When in this position, the tone arm may be swung in azimuth 60 throughout an angle determined by the length of the slots 15, whose length, of course, may be varied as desired. The pins, of course, will engage the shoulders 15, at the ends of the slots and limit the move-

ment of the tone arm. Thus assembled, the sound tube may be rocked in the vertical through the desired angle.

It will be seen that the parts employed are very simple, very easily manufactured, and 70 no special effort or care must be taken to determine accuracy in the fitting of the parts. Also, the sound tube can be moved through the desired angles without any danger of being accidentally separated from the machine 75 proper. In fact, it will be impossible to accidentally disconnect the parts, whereas, if it is desired to disconnect them, it can be done very quickly and very conveniently.

I have shown and described a particular 80 embodiment of my invention and certain details for the purpose of better explaining my invention. It will be understood by those skilled in the art that numerous and extensive departures may be made from the form 85 and details without departing from the spirit of the invention.

I claim:—

1. In a phonograph, the combination of an 90 amplifier and a sound conveyor and means to connect said parts together, including a hollow bushing having portions of its top edge cut away to form slots, pins on the sound conveyor placed in said slots when the parts are assembled, a collar and means to connect 95 the collar to the top of the bushing, an inwardly turned flange on said collar fitting over the top of the pins when the parts are assembled and closing the slots in the top of the bushing. 100

2. In a phonograph, the combination of an 105 amplifier and a sound conveyor, a hollow bushing connected at one end to the body portion of the amplifier and at the other end to the sound conveyor, said hollow bushing having its top edge cut away in places to form slots, said slots being diametrically opposite each other, pins placed in said slots when the parts are assembled, a collar and means to connect the collar to the top of the bushing, and an inwardly turned flange on the top of the collar extending over the ends of the pins when the parts are assembled, retaining said pins in position and closing the tops of the slots. 110

3. In a phonograph, the combination of a tone arm, a sound box on one end of the tone arm, a collar on the other end of the tone arm of greater diameter than the maximum part of the tone arm, the outside surface of said collar being curved with the maximum diameter at the center, a hollow bushing for connecting said tone arm to said phonograph, the bore in the bushing being of substantially the same diameter as the maximum 120 diameter of the collar on the tone arm, the upper edge of the bushing being cut away to form slots, the upper edge of the bushing between the ends of the slots forming arc-shaped lugs whose inner surfaces engage the 125 130

outer surface of the collar and prevent its rattling in the bushing, pins projecting from the collar on the tone arm into said slots and means to cover the tops of the slots and the 5 ends of the pins to retain the tone arm on the bushing.

4. In a phonograph, a movable tubular tone arm having a vertical section, a stationary tubular extension of the tone arm into 10 which the end of the movable arm telescopically projects and in which stationary arm the movable arm rotates about a vertical axis, bearing members projecting radially from opposite sides of the movable arm in a 15 plane perpendicular to the stationary arm and extending into the stationary arm be-

yond the inner walls of the stationary arm, notches in the end of said stationary arm for receiving said bearing members, said notches having sides upon which the said 20 members rest and slide in the segment of a circle about the perpendicular axis of the stationary arm whenever the movable arm is moved about its vertical axis, and a cap for the stationary arm, threads for holding the 25 cap in place on the end of the stationary arm and closing the open sides of said notches to lock the bearing members in the said notches.

In witness whereof, I have hereunto signed my name this 25 day of September, 1916.

LOUIS P. VALIQUET.
